M. BAUER.
ROOF JACK.
APPLICATION FILED DEC. 21, 1914.

Patented May 15, 1917.

UNITED STATES PATENT OFFICE.

MARTIN BAUER, OF CLEVELAND, OHIO.

ROOF-JACK.

1,226,169.

Specification of Letters Patent.

Patented May 15, 1917.

Application filed December 21, 1914. Serial No. 878,437.

To all whom it may concern:

Be it known that I, MARTIN BAUER, a citizen of the United States, and resident of Cleveland, in the county of Cuyahoga and 5 State of Ohio, have invented certain new and useful Improvements in Roof-Jacks, of which I hereby declare the following to be a full, clear, and exact description, such as will enable others skilled in the art to which 10 it appertains to make and use the same.

The objects of the invention are to provide a roof jack or bracket for use upon slated or shingled roofs which is readily applied thereto and detachable therefrom, and 15 provides means for supporting a plank in the horizontal position which serves as a scaffold upon which a workman can operate upon the roof to repair the same or to paint portions of the house which are otherwise 20 difficult of access.

The invention comprises means for adjusting the bracket to adapt it to roofs of varying pitch so that the plank supporting member will always remain level, and also 25 means for engaging the lower ends of a ladder to retain the same when laid upon the roof.

It also comprises the details of construction and combination and arrangement of 30 parts hereinafter described, shown in the accompanying drawings and specifically pointed out in the claims.

In the accompanying drawings Figure 1 is a perspective view showing the device 35 mounted upon a slate roof; Fig. 2 is an enlarged view of the device; Fig. 3 is a side elevation thereof; Fig. 4 is a perspective view of the blade by means of which the bracket is attached to the roof; Fig. 5 is a 40 front elevation of one of the folding ladder supporting attachments; Fig. 6 is a side elevation thereof; Fig. 7 is a transverse section of the attaching blade and its support showing means for adjusting the blade; Fig. 8 is a detail view of the connecting 45 rivet therefor; Fig. 9 is a transverse section of the blade and bar showing the cup shaped recess in the bar and securing bolt for the blade affording a close frictional grip to 50 prevent slipping; Fig. 10 is a front elevation of the jack showing rack adjustment therefor.

In these views the bracket is T shaped and comprises preferably a bar A, the extremity of which is attached by riveting or

otherwise to an angle bar B which forms the cross bar of the T. C is the blade by means of which the bracket is attached to the roof.

The body portion can be formed of any 60 suitable metal of sufficient thickness to be rigid, but the blade C is preferably formed of a thin and flat band of spring steel, and is adjustable upon the bar A by means of the slot C' in the blade, and thumb nut, C² 65 and screw C³ secured in the bar A, which also forms a clamping means for the blade. A projecting keeper C⁴ at the inner extremity of the blade passes through the slot a in the bar A and serves to keep the parts in 70 alinement and permits the blade to slide freely upon the bar.

Ribs R, R, are formed on the faces of 75 blade C and bar A to insure rigidity thereof. See Fig. 4.

The outer extremity of the blade is inserted underneath the shingles or slate of a roof as at S in Fig. 1 and will engage with one of the nails as at S' and will prevent the bracket from being withdrawn. Since 80 slate are made in several sizes it is advisable to supply the blade with a series of similar notches c', c' intermediate of its ends so that at least one of them can be made to engage with a nail in the roof and retain the bracket 85 in place.

A brace member A³ preferably connects the bar A and cross bar B to preserve the required rigidity of the parts.

The platform D which supports one end 90 of the plank and is designed to always remain level without reference to the pitch of the roof upon which the bar A rests, is adjustably supported by means of a bar E which is pivoted at the forward end upon a 95 raised bearing member F upon the forward end of the bar A, and at its rear extremity the bar E is adjustably mounted for vertical elevation and depression by means of two vertically engaging racks, G and H, one of 100 which is pivoted at its upper end to the outer extremity of the bar E, and the other is pivoted at its lower end to the bearing I upon the cross bar B.

The racks are loosely assembled by means 105 of an encircling member M and are slidably movable upon each other. A cam K pivoted in the member M serves to clamp them in the adjusted position. See Fig. 10.

A projection G' upon the upper rack 110

engages the outer edge of a board if it should be desired to use one laid across the platform D. The front wall of the angle bar B is longitudinally slotted at B⁵ B⁵ and 5 pointed dogs L, L, are supported upon said bar and are made adjustably movable thereon by means of clamping bolts 1 and nuts 1'.

The pointed dogs are designed to rest in 10 the crevices between the slate as shown in Fig. 1 and to assist the hooked blade C in holding the bracket in place.

The plank is extended over two of the 15 brackets or a bracket can be used alone as a seat or to support one end of a plank, the other end of which may rest upon some portion of the building. A ladder can also be supported by the bracket.

To facilitate the use of a ladder folding 20 arms W, W, may be pivoted to the extremities of the bar B and the feet of the ladder can rest upon them.

An extension w on each arm W prevents 25 it from folding outward when the weight of the ladder is brought to bear upon it. See Figs. 5 and 6.

The bolt C³ passes through a cup shaped elevation C⁵ upon the bar A and when the blade is clamped tightly the blade is drawn 30 into the recess, thus preventing slipping of the parts, which would be exceedingly dangerous to the user.

Having described the invention what I 35 claim as new and desire to secure by Letters Patent is:

1. In a roof jack, in combination, a T-shaped base plate, a thin flexible blade adjustably secured to the center arm of said base plate, said flexible blade having a hook 40 in its edge, pointed dogs laterally adjustable upon the cross arm of said base plate, a plank supporting member pivoted in the outer end of said base plate, and a longitudinally adjustable arm having one end

pivotedly attached to said cross arm and the other end to said plank supporting member. 45

2. In a roof jack, in combination, a T-shaped base plate, a thin blade longitudinally adjustable upon the center arm of said base plate and having an inclined slot in 50 one edge forming a retaining hook, laterally movable dogs adjustably secured in the cross arm of said base plate, a plank supporting member pivoted in the outer extremity of the long arm of said base plate, 55 and a divided arm connecting said cross bar and outer end of said plank supporting member, engaging racks upon the portions of said divided arm and means for rigidly engaging said racks with each other. 60

3. In a roof jack, a T-shaped bed plate, a thin metal blade longitudinally adjustable upon the long arm of said bed plate, said blade provided with a nail engaging means, means for securing said blade and arm 65 rigidly together, a plank supporting member pivoted in the long arm of said bed plate, and means for adjustably supporting the outer end of said plank supporting member upon said base plate. 70

4. In a roof jack, in combination, a T-shaped base plate, a thin metal blade longitudinally adjustable upon the long arm, means for securing the same in selected positions, means upon said blade for engaging a nail, a plank supporting member pivotally connected with said bed plate, means for adjustably supporting the front extremity of said plank supporting member 75 upon said bed plate, and laterally movable gripping dogs adjustably secured in the cross bar of said bed plate. 80

In testimony whereof, I hereunto set my hand this 14th day of November, 1914.

MARTIN BAUER.

In presence of—
W.M. J. KLOTZBACH,
W.M. M. MONROE.
